ATTORNEY.

UNITED STATES PATENT OFFICE

119,884

DESIGN FOR A TOM AND JERRY BOWL

Kameniro Kame, Los Angeles, Calif.

Application October 13, 1939, Serial No. 87,651

Term of patent 7 years

To all whom it may concern:

Be it known that I, Kameniro Kame, a subject of the Emperor of Japan, residing at Los Angeles, in the county of Los Angeles and State of California, have invented a new, original, and ornamental Design for a Tom and Jerry Bowl, of which the following is a specification, reference being had to the accompanying drawing, forming part thereof.

The figure is a perspective view of the bowl showing my design.

I claim:

The ornamental design for a Tom and Jerry bowl, as shown.

KAMENIRO KAME.
